UNITED STATES PATENT OFFICE.

OTTO W. SCHAUM, OF PHILADELPHIA, PENNSYLVANIA.

JACQUARD APPARATUS FOR LOOMS.

SPECIFICATION forming part of Letters Patent No. 531,390, dated December 25, 1894.

Application filed May 13, 1893. Serial No. 474,123. (No model.)

To all whom it may concern:

Be it known that I, OTTO W. SCHAUM, a citizen of the United States, residing at Philadelphia, in the county of Philadelphia and 5 State of Pennsylvania, have invented a certain new and useful Improvement in Jacquard Apparatus for Looms, of which the following is a true and exact description, reference being had to the accompanying drawings, which 10 form a part of this specification.

My invention relates to Jacquard machines and is especially adapted to be used in connection with a style of jacquard known as a rise and fall machine and of a general character 15 similar to that shown in the patent to Stafford & Barker, No. 236,375, and dated January 4, 1881. One of the disadvantages attendant on the use of this machine has been, that the harness cords being constantly 20 in motion both ways rub continuously on the holes in the compart board through which they pass, and rapidly wear out, not lasting more than half the time that the cords in single lift do. To obviate this difficulty I 25 arrange my compart board so that it may be moved in unison with the harness cords or in unison with at least the major part of the cords.

My invention is best understood as described in connection with the accompanying drawings illustrating a Jacquard machine embodying my invention, and in which—

Figure 1 is a view of a Jacquard machine and part of a loom showing a connection from 35 the driving shaft which communicates motion to the jacquard to the compart board whereby the board moves in unison with a hook plate. Fig. 2 is a similar view showing a connection between the upper hook plate or the griff 40 plate and the compart board; and Fig. 3 is a similar view showing the preferred form where connection is arranged between the lower hook plate and the griff board.

A, is a beam or cross bar for supporting the 45 pattern mechanism.

J represents a cylinder and K a series of cards operating in a well known manner to cause separate hooks to be raised in accordance with the pattern required.

50 S is a driving shaft having cranks as S' S² which serve to operate levers B' B² by means

of rods or links r' r². The levers B' B² which are pivoted at c' c² respectively serve to raise and lower the upper and lower hook plates P' P² which act on the hooks put in their path 55 by the action of the pattern cards K and through the hooks operate the harness cords H which pass through holes as indicated at h in the compart board C. These harness cords in their rapid movement through the holes h 60 rub and wear particularly in rise and fall machines where one part of the cords fall while the other part rises. In this sort of machine it is usual to permit the heaviest work or the greatest number of cords to be constantly 65 moved in one direction, and for purposes of convenience by dropping instead of raising the threads by means of the harness. In order to prevent this excessive wear I make the compart board C vertically movable preferably 70 guiding it in any suitable guides as G placed on the loom frame and raise and lower it in unison with the harness cords. To move it in this manner it may be connected and move with either of the hook plates P' or P² 75 as desired by attaching carriers C' or C² to pivots b' or b² on said hook plates as shown in Figs 3 and 2, or if preferred the compart board may be raised and lowered from any suitable part of the machine as by eccentrics 80 E placed on the shaft S.

Inasmuch as it is usual, as has been stated, to do the heaviest work by dropping the threads it would usually be more advantageous to connect the compart board to the 85 lower hook plate so that it will move in unison with the cords permitted to drop by the downward movement of said plate.

I am aware that movable compart boards with a series of slotted holes formed therein 90 have been employed to aid in selecting certain of the harness cords and raise the warp threads connected thereto so as to make a pattern. In my arrangement, however, the compart board is provided with a series of 95 unslotted holes which have no function except to guide the cords, and the compart board is made movable with a hook plate so as to diminish the wear which results when the cords are drawn rapidly through the holes in 100 the board.

Having now described my invention, what

I claim as new, and desire to secure by Letters Patent, is—

1. The combination with the hooks of a rise and fall Jacquard machine and the harness cords secured thereto, of upper and lower hook plates adapted to operate the hooks, a compartment board having a series of unslotted holes through which the harness cords pass freely and whose function is to guide said cords, and a connection to some moving part of the loom for moving the compartment board in unison with one of said hook plates, substantially as and for the purpose specified.
2. The combination with the hooks of a rise and fall Jacquard machine and the harness cords secured thereto, of upper and lower hook plates adapted to operate the hooks, a compartment board having a series of holes through which said harness cords are adapted

to pass and whereby they are guided, and means for moving said compartment board in unison with the lower hook plate substantially as and for the purpose specified.

3. The combination with the hooks of a Jacquard machine and the harness cords operated thereby, of upper and lower hook plates adapted to operate the hooks, a compartment board through which the harness cords are adapted to pass freely, a connection between the lower hook plate and the compartment board whereby they are both moved together, and guides for the compartment board substantially as specified.

OTTO W. SCHAUM.
